UNITED STATES PATENT OFFICE.

DAVID MCKENNA, OF WATERBURY, CONNECTICUT, ASSIGNOR OF ONE-HALF
TO JAMES MCGEE, OF WATERBURY, CONNECTICUT.

SCISSORS OR SHEARS.

SPECIFICATION forming part of Letters Patent No. 702,238, dated June 10, 1902.

Application filed November 7, 1901. Serial No. 81,459. (No model.)

To all whom it may concern:

Be it known that I, DAVID MCKENNA, a citizen of the United States, residing at Waterbury, county of New Haven, State of Connecticut, have invented a new and useful Scissors or Shears, of which the following is a specification.

My invention relates to the manufacture of scissors and shears; and has for its object to provide simple and inexpensive means for preventing the pivot from turning. It is of course well understood that the pivot in ordinary scissors and shears, more especially the lower grade of both scissors and shears, is a screw-stud upon which one blade, ordinarily the lower blade when the shears are held in the horizontal plane, is pivoted, the threaded end of the stud engaging the other blade, in the present instance the upper blade, and being held against turning loose by riveting or heading down the threaded end upon the outer face of the upper blade. This method of securing the stud against turning loose is objectionable for three reasons: In the first place, the headed end of the stud always looks rough and unfinished and renders it impossible to give a neat and finished appearance to that side of the shears; in the second place, the headed end of the stud is frequently so jagged and sharp that it will tear the skin and cause serious inconvenience by catching on fine goods—as, for example, upon silk, flosses, fine yarns, &c.—and, in the third place, the heading frequently does not hold, so that there is constant trouble caused by the pivots becoming loose and turning sufficiently to loosen the blades. My present invention provides a simple and inexpensive means of overcoming these objections and insures that without appreciable difference in the cost of production the pivots shall be securely but detachably retained in place—that is, securely retained under the conditions of use, but in such a manner as to permit their convenient removal should it be desired to separate the blades for sharpening or for any purpose whatever, the fastening furthermore being of such a nature as not to be to the slightest degree offensive to the eye, but rather to add to the general attractiveness of the shears and being wholly out of the way, so that danger of tearing the

skin or the catching of silks, flosses, or yarns thereon shall be wholly avoided.

In order to accomplish the desired result, I have devised the novel pivot-fastening device, 55 of which the following description, in connection with the accompanying drawings, is a specification, reference characters being used to designate the several parts:

Figure 1 is an elevation of a pair of shears, 60 illustrating the application thereto of my novel pivot-fastening device; Fig. 2, a longitudinal section, on an enlarged scale, on the line 2 2 in Fig. 1; and Fig. 3 is a transverse section, on an enlarged scale, on the line 3 3 in 65 Fig. 1.

A denotes one of the blades of a pair of scissors or shears, which for convenience I will term in this instance the "under" blade, B the other blade, which for convenience I will 70 term in this instance the "upper" blade, and C the pivot. The pivot, which is a screw-stud, is provided with a head 10, which is recessed into the under blade and is provided with the usual slot 11, by which it is turned to place 75 by a screw-driver.

12 denotes the threaded end of the pivot, which is shown as engaging the upper blade. The novel feature of my invention consists in providing this threaded end of the stud 80 with an open recess or groove 13, which is engaged by a removable retaining device 14 to prevent the pivot from turning. The exact construction of this removable retaining device is not of the essence of my invention, it being simply required that a device be provided which shall normally rest in the groove or recess in the threaded end of the pivot to retain the pivot against turning and shall be conveniently removable, so as to permit the removal of the pivot should it be required for any purpose to separate the blades. In the present instance I have shown a retaining device consisting of a spring lying in a slot 15 in the face of the upper blade, the free end 90 of said spring resting in and engaging the groove 13 and being provided with a loop or eye 16 for convenience in lifting the retaining device out of groove 13 should it be required to turn out the pivot or give it a partial rotation to adjust it. The retaining device may be soldered or retained in place in 95 100

any suitable manner. In the present instance I have shown the retaining device as secured to the blade by means of a rivet 17, lying wholly below the surface of the blade, the 5 retaining device being shown as provided with a ring 18, through which the rivet passes, the head of the rivet and the ring lying in an enlargement 19 of slot 15, the end of the pivot, the rivet, and the whole of the retaining device, with the exception of eye 16, lying below or flush with the surface of the blade, 10 and a small rounded portion only of the eye lying above the surface of the blade for convenience in manipulation, as already described.

Having thus described my invention, I claim—

1. The combination with the blades of scissors and shears, of a pivot upon which one of 20 the blades turns and which is provided with a threaded end to engage the other blade and an open groove or recess in its end, and a removable spring retaining device which engages the groove to prevent the pivot from 25 turning, and which may be lifted from said groove to enable the pivot to be adjusted.

2. The combination with the blades of scissors and shears, of a pivot upon which one of the blades turns and which is provided with a threaded end to engage the other blade and 30 an open groove or recess in its end, and a removable spring retaining device recessed into the blade and engaging the groove to prevent the pivot from turning, and which may be lifted from said groove to enable the pivot 35 to be adjusted.

3. The combination with the blades A and B of scissors and shears, said blade B having a slot 15, of a pivot upon which blade A turns and which is threaded to engage blade B, the 40 threaded end of the pivot having an open groove or recess 13 in its end, and a spring retaining device rigidly secured in slot 15, the free end of said retaining device engaging the groove 13 to prevent the pivot from 45 turning.

In testimony whereof I affix my signature in presence of two witnesses.

DAVID MCKENNA.
